COMBINED STAND AND COVER FASTENER FOR A REFUSE CAN OR THE LIKE

Julian J. Acree, Okmulgee, Okla.

Application October 1, 1959, Serial No. 57,749

Term of patent 14 years

(Cl. D58—26)

Figure 1 is a perspective view of a combined stand and cover fastener for a refuse can or the like showing my new design;

The can is shown in Figures 1 and 3 for illustrative purposes only.

I claim:

The ornamental design for a combined stand and cover fastener for a refuse can or the like, as shown and described.
